The ornamental design for a charging and replacing station for mobile battery, as shown and described.

DESCRIPTION

FIG. 1 is a front and right perspective view of a charging and replacing station for mobile battery, showing my new design.

FIG. 2 is a rear and right perspective view thereof.

FIG. 3 is a front and left perspective view thereof.

FIG. 4 is a rear and left perspective view thereof.

FIG. 5 is a front elevation view thereof.

FIG. 6 is a left side elevation view thereof.

FIG. 7 is a right side elevation view thereof; and,

FIG. 8 is a top plan view thereof.

The broken lines shown in the drawings illustrate portions of the charging and replacing station for mobile battery that form no part of the claimed design.

1 Claim, 8 Drawing Sheets(56)
